UNITED STATES PATENT OFFICE

113,506

DESIGN FOR A LOCKET

Oscar M. Burke, New York, N. Y.

Application December 20, 1938, Serial No. 81,894

Term of patent 7 years

To all whom it may concern:

Be it known that I, Oscar M. Burke, a citizen of the United States, residing at New York, in the county of New York and State of New York, have invented a new, original, and ornamental Design for a Locket, of which the following is a specification, reference being had to the accompanying drawing, forming part thereof.

In the drawing—

Fig. 1 is a front view of a locket showing my new design, the design on the rear of said locket being identical of the design on the front face thereof.

Fig. 2 is a side view.

I claim:

The ornamental design for a locket, as shown and described.

OSCAR M. BURKE.
